AUTOMOTIVE VEHICLE INSIDE DOOR HANDLE

Albert J. Gonas, Detroit, Mich., assignor to General Motors Corporation, Detroit, Mich., a corporation of Delaware

Application October 12, 1949, Serial No. 5,446

Term of patent 7 years

(Cl. D10—8)

To all whom it may concern:

Be it known that I, Albert J. Gonas, a citizen of the United States, and a resident of Detroit, State of Michigan, have invented a new, original, and ornamental Design for an Automotive Vehicle Inside Door Handle, of which the following is a specification, reference being made to the accompanying drawing, forming a part thereof.

In the drawing:

Figure 1 is a plan view of an automotive vehicle inside door handle, showing my new design.

Figure 2 is a side elevation thereof.

Figures 3 and 4 are sectional views taken substantially on lines 3—3 and 4—4 respectively of Figure 2.

I claim:

The ornamental design for an automotive vehicle inside door handle, substantially as shown.
ALBERT J. GONAS.
